DESIGN FOR A FUEL FEED CONTROL DEVICE

Horace A. Stukes, San Antonio, Tex.

Application February 14, 1938, Serial No. 75,125

Term of patent 14 years

To all whom it may concern:

Be it known that I, Horace A. Stukes, a citizen of the United States, residing at San Antonio, in the county of Bexar and State of Texas, have invented a new, original, and ornamental Design for a Fuel Feed Control Device, of which the following is a specification, reference being had to the accompanying drawing, forming part thereof, wherein:—

Figure 1 is a side elevation of the fuel feed control device embodying the invention.

Figure 2 is a side elevation taken at right angles to the form shown in Figure 1, and

Figure 3 is a plan view.

I claim:

The ornamental design for a fuel feed control device as shown.

HORACE A. STUKES,
